(57) CLAIM

The ornamental design for a planter, as shown and described.

DESCRIPTION

FIG. 1 is a front perspective view of a planter showing the present invention;

FIG. 2 is a front view thereof;

FIG. 3 is a rear view thereof;

FIG. 4 is a right side view thereof, the left side view being identical thereto; and,

FIG. 5 is a bottom view thereof.

The portions of the figures illustrated in broken lines illustrate portions of the planter which form no part of the claimed subject matter.

1 Claim, 5 Drawing Sheets

FIG. 1

FIG. 2

FIG. 3

FIG. 4

FIG. 5
